The ornamental design for a fascia-mounted gutter debris barrier system, as shown and described.

DESCRIPTION

FIG. 1 is a top, front, right isometric view of a fascia-mounted gutter debris barrier system showing my new design;

FIG. 2 is a right elevation thereof;

FIG. 3 is a left elevation thereof; and,

FIG. 4 is a top plan view thereof.

The fascia-mounted gutter debris barrier system is shown with a symbolic break to its length. The appearance of any portion of the article beyond the break line forms no part of the claimed design. Additionally, the broken lines in the drawings depict portions of the fascia-mounted gutter debris barrier system that form no part of the claimed design.
